(57) CLAIM

We claim the ornamental design for a vest with pacifier holder, as shown and described.

DESCRIPTION

FIG. 1 is a perspective view of a vest with pacifier holder, showing the new design;

FIG. 2 is a front elevational view thereof;

FIG. 3 is a rear elevational view thereof;

FIG. 4 is a right-side elevational view thereof;

FIG. 5 is a left-side elevational view thereof;

FIG. 6 is a top plan view thereof; and,

FIG. 7 is a bottom plan view thereof.

The broken lines showing a baby with a pacifier in FIG. 1 and a plush form of a dog in the figures depict environmental matter, and form no part of the claimed design.
